RAZOR BLADE SHARPENER

Frank E. Wolcott, West Hartford, Conn.

Application March 8, 1930, Serial No. 434,304

31 Claims. (Cl. 51—80)

My invention relates to razor blade sharpeners.

It has among its objects to provide an improved razor blade sharpener of the type having a casing carrying sharpener rolls and pivoted flaps on said casing carrying blade engaging means or rolls co-operating with the rolls in said casing. A further object of my invention is to provide improved means for controlling the flaps of such a sharpener whereby the flaps may be disposed and retained in closed position while being readily depressible at will to vary the pressure on the blade being sharpened, and also readily openable when desired. A still further object of my invention is to provide improved co-operating spring and holding means for the flaps, one co-operating with the other and having the spring means adapted to permit depression of the flap to vary the pressure on the blade and the holding means, preferably in the form of controlling push button mechanisms, operative to hold the flaps in closed position while permitting this depression and also operative to release the flaps for automatic opening by said spring means. Still another object of my invention is to provide such a construction wherein these flap controlling means are operatively connected between the flaps and the casing in such manner as to permit the use of rigid blade positioning pins and without requiring any co-operation of or contact between the blade positioning pins and the flaps. These and other objects and advantages of my improved construction will, however, hereinafter more fully appear.

In the accompanying drawing I have shown for purposes of illustration one embodiment which my invention may assume in practice.

In this drawing:—Fig. 1 shows a top view of the device. Fig. 2 shows a side view with the cover flaps closed and a razor blade with its cutting edges located between the pairs of rolls. Fig. 3 is a side view of the casing with the cover flaps open. Fig. 4 is a section on the plane indicated by the dotted line 4—4 on Fig. 1. Fig. 5 is a section on the plane indicated by the dotted line 5—5 on Fig. 1. Fig. 6 is a perspective view of one of the cover flaps and the spring which tends to throw it open.

The casing which is illustrated has a curved bottom wall 1 with upwardly curved ends, and side walls 2. The cover flaps have side walls 3 and flat tops 4 that at their outer ends 5 are curved downwardly on the same arcs as the ends 55 of the bottom wall of the casing. The flaps turn

on pivot studs 6 that extend through the sides of the casing.

The lower rolls 7 are mounted on axles 8 that extend inward from the side walls of the casing. Fastened to the axle of one of the lower rolls is a crank arm 9 that has a handle 10. The upper rolls 11 are mounted on axles 12 that extend inward from the side walls of the flaps. Wound spirally on the rolls shown are strips of leather 13.

Fastened to the axles of the lower rolls are gears 14 that are connected by gears 15, and fastened to the upper rolls are gears 16 that are connected with the gears of the lower rolls by gears 17 so that when the crank is turned all of the rolls are rotated. Pins 18 project upward from the bottom of the casing for receiving the blade to be sharpened.

In the device shown springs 20 are coiled about the pivot studs 6 on one side, in such manner that their lower ends bear down against the bottom of the casing while their upper ends press upward against the under faces of the flaps. The curved ends of the flaps have slots 21, and extending into these slots are the shanks of push buttons 22 that are located in sockets in the ends of the casing and are normally thrust outward by springs 23. The shanks of the push buttons are of less diameter than the width of the slots, while on the inner ends of the shanks are heads 24 that are larger in diameter than the width of the slots. When the flaps are closed the push buttons are pressed outward by their springs so that these heads 24 will be engaged by the edges of the flaps and will hold the flaps closed.

By pressing the buttons inward, as by the pressure of the thumb and finger of a person holding the casing, the heads of the buttons are moved inward from the edges of the flaps and then the flaps are free to be thrown open by their springs.

Thus it will be observed that when the flaps are closed the same automatically snap into and are retained in closed position, while when the push buttons are pushed in, the flaps are automatically released and moved by their springs to full open position, ready to permit the insertion or removal of a blade. Attention is also directed to the fact that the ends of the slots 21 engage the shanks of the push buttons in such manner as to prevent conflict of the depending ends of the flaps with the rolls in the casing, while the heads 24 on the push button shanks, being pressed against the edges of these slots by their springs, co-operate with the spring means 20 in holding the flaps in their open position. It will, of course, also be evident that

in this construction the flap controlling mechanism described, being operatively connected between the casing and flaps, is in no way dependent upon the blade positioning pins 18 which, if desired, may accordingly be rigid pins and terminate substantially below the flaps as illustrated herein. Attention is further directed to the fact that when a blade is in the stopper, since all of the leather strips 13 will then engage the edge of the blade and the flaps thus cannot drop down as shown in Fig. 4, the flaps will then occupy a closed position slightly above the position shown in Fig. 2 in such manner as to space the adjacent edges of the flaps from one another and thereby permit downward pressure of the flaps against the springs 20 to vary the pressure on the blade as desired. These and other advantages of my improved construction will, however, be clearly apparent to those skilled in the art.

While I have herein described one embodiment which my invention may assume in practice, it will be understood that this form of the same is shown for purposes of illustration and that the invention may be modified and embodied in other forms without departing from its spirit or the scope of the appended claims.

The invention claimed is:

1. A razor blade sharpener having a casing, cover flaps pivoted to the casing, blade engaging means comprising a pair of rolls mounted in the casing, blade engaging means separately carried by different flaps and co-operating with said rolls, gearing connecting the rolls, means for rotating the rolls, means normally tending to throw the flaps open, and means on said casing and controlled by said flaps for retaining the flaps closed.

2. A razor blade sharpener comprising a casing having blade engaging means comprising sharpening rolls therein, a plurality of pivoted flaps thereon carrying blade engaging means cooperating with said rolls, blade locating means, and means automatically made operative by movement of said flaps into a closed position for retaining said flaps in a closed position.

3. A razor blade sharpener having a casing, cover flaps pivoted to the casing, blade engaging means comprising a pair of rolls mounted in the casing, blade engaging means separately carried by different flaps and co-operating with said rolls, gearing connecting the rolls, means for rotating the rolls, spring means thrusting between the casing and flaps for throwing the flaps open, and means on said casings and acting on the remote ends of different flaps for retaining the flaps closed.

4. A razor blade sharpener comprising a casing having end walls, cover flaps pivoted to the casing and having depending end portions movable inside the end walls of the latter and forming a continuation of said end walls in the closed positions of the flaps, blade engaging means comprising sharpening rolls mounted in the casing, blade engaging means on said flaps cooperating with said rolls, means for rotating said rolls, and vertical slot and pin connections between said depending portions and said casing limiting the movement of said flaps.

5. A razor blade sharpener comprising a casing having end walls, cover flaps pivoted to the casing and having depending end portions movable inside the end walls of the casing and having slots in said depending portions, blade engaging means comprising rolls mounted in the casing, blade engaging means on said flaps cooperating

with said rolls, means for rotating said rolls, and positioning means for said flaps holding the same in a closed position and having members on the casing projecting into said slots as said flaps are moved about their pivots and cooperating spring means tensioned as said flaps are moved about their pivots toward said rolls and relative to said members. 80

6. A razor blade sharpener comprising a casing having end walls substantially closing the casing ends, cover flaps pivoted to the casing and having depending end portions movable inside the end walls of the latter toward the center of the casing upon opening said flaps, blade engaging means comprising sharpening rolls mounted in the casing on axes parallel to said end walls, blade engaging means on said flaps cooperating with said rolls, means for operating the rolls, and means for inhibiting conflict of said depending portions with the rolls in the casing in the open 95 position of said flaps. 85

7. A razor blade sharpener having a casing, cover flaps pivoted to the casing, blade engaging means comprising a pair of rolls mounted in the casing, blade engaging means separately carried 100 by different flaps and co-operating with said rolls, gearing connecting the rolls, means for rotating the rolls, spring means thrusting between the casing and flaps for throwing the flaps open, and push button operated manually releasable means 105 in the casing automatically actuated by said flaps to retain the latter closed.

8. A razor blade sharpener having a casing, cover flaps pivoted to the casing, a pair of rolls mounted in the casing, a pair of rolls having 110 different rolls separately carried by different flaps, gearing connecting the rolls, means for rotating the rolls, springs thrusting between the casing and flaps for throwing the flaps open, and operating means having operating connections 115 extending through the casing into the path of and obstructing the opening movements of the flaps for retaining the flaps closed.

9. A razor blade sharpener having a casing, cover flaps pivoted to the casing, a pair of rolls 120 mounted in the casing, a pair of rolls having different rolls separately carried by different flaps, means for rotating the rolls, springs for throwing the flaps open, and means inside said casing and controlled by said flaps for holding the 125 flaps closed.

10. A razor blade sharpener having a casing, cover flaps pivoted to the casing, a pair of rolls mounted in the casing, a pair of rolls carried by said flaps, gearing connecting the rolls, means 130 for rotating the rolls, spring means thrusting between the casing and each flap for throwing the flaps open, and push buttons mounted in the casing and extending into the paths of the inner edges of the flaps for retaining the flaps closed. 135

11. A razor blade sharpener having a casing, cover flaps pivoted to the casing, said flaps having slots in their inner ends, a pair of rolls mounted in the casing, a pair of rolls carried by said flaps, gearing connecting the rolls, means for 141 rotating the rolls, spring means arranged to open the flaps, and push buttons with shanks smaller than the width of the slots and heads larger than the width of the slots, whereby when said buttons are in one position said spring means will open the flaps and when in another position said heads will engage with and hold the flaps closed.

12. A razor blade sharpener having a casing with curved ends, cover flaps pivoted to the casing, said flaps having ends curved so as to turn 145

- within said ends of the casing, a pair of rolls mounted in the casing, a pair of rolls carried by said flaps, gearing connecting the rolls, means for rotating the rolls, means normally tending to throw the flaps open, and means mounted on the casing and having portions engaging the curved inner ends of the flaps for retaining the flaps closed. 13. A razor blade sharpener having a casing with sockets in its ends, push buttons in said sockets, cover flaps pivoted to the casing, a pair of rolls mounted in the casing, a pair of rolls carried by said flaps, gearing connecting the rolls, means for rotating the rolls, means normally tending to throw the flaps open, and means operated by said push buttons and engaging said flaps for retaining the flaps closed. 14. A razor blade sharpener having a casing with sockets in its ends, push buttons in said sockets, cover flaps pivoted to the casing, a pair of rolls mounted in the casing, a pair of rolls carried by said flaps, gearing connecting the rolls, means for rotating the rolls, and means normally tending to throw the flaps open, said push buttons having operatively connected means in normal position engaging said flaps and obstructing the opening movements of the flaps. 15. A razor blade sharpener having a casing, a plurality of openable covers connected to the casing, blade engaging means comprising a pair of rolls mounted in the casing, blade engaging means separately carried by different covers and cooperating with said rolls, gearing connecting the rolls, means for rotating the rolls, means normally tending to open the covers, and a plurality of separately operable manually releasable abutment means normally disposed in the path of movement of said covers toward open position for retaining the covers closed. 16. A razor blade sharpener having a casing, cover flaps pivoted to said casing and having resilient means normally holding the same in open position, rolls carried by said casing, rolls separately carried on different flaps, means for rotating said rolls, and automatically operated means controlled by said flaps disposed inside said casing and releasable from the exterior thereof for securing said flaps in closed position. 17. A razor blade sharpener having a casing, cover flaps pivoted to said casing and having resilient means normally holding the same in open position, rolls carried by said casing, rolls separately carried on different flaps, means for rotating said rolls, automatically operated means inside said casing and controlled by said flaps for securing said flaps in closed position, and push button operated means operable from the exterior of said casing for releasing said last mentioned means. 18. A razor blade sharpener having a casing, cover flaps pivoted to said casing and having resilient means normally holding the same in open position, rolls carried by said casing and cover flaps, means for rotating said rolls, and resiliently mounted abutment means controlled by said flaps and automatically operative to hold the same in closed position. 19. A razor blade sharpener having a casing, cover flaps pivoted to said casing and having resilient means normally holding the same in open position, rolls carried by said casing and cover flaps, means for rotating said rolls, resiliently mounted abutment means controlled by said flaps and automatically operative to hold the same in closed position, and push button means for releasing said last mentioned means. 20. A razor blade sharpener having a casing, cover flaps pivoted to said casing and having resilient means normally holding the same in open position, rolls carried by said casing and cover flaps, means for rotating said rolls, resiliently mounted abutment means controlled by said flaps and automatically operative to hold the same in closed position, and push button means for releasing said last mentioned means, both of said last two means being carried by said casing. 21. A razor blade sharpener having a casing, cover flaps pivoted to said casing, blade engaging means comprising rolls carried by said casing, blade engaging means separately carried on different flaps and co-operating with said rolls, means for rotating said rolls and manually releasable means controlled by said flaps and automatically movable into holding position relative to said flaps when the same are moved into closed position. 22. A razor blade sharpener having a casing, cover flaps pivoted to said casing, blade engaging means comprising rolls carried by said casing, blade engaging means separately carried on different flaps and co-operating with said rolls, means for rotating said rolls, resiliently mounted means controlled by said flaps and automatically movable into holding position beneath said flaps when the same are moved into closed position, and push button means for releasing said last mentioned means. 23. A razor blade sharpener having a casing, a plurality of cooperating covers on said casing, cooperating operatively connected rolls mounted in said casing and on said covers and having connections for operation from the exterior of said casing, manually controllable means for retaining said covers in closed position disposed in the path of portions of said covers when moving out of said position, and means for moving said covers upon release of said retaining means toward the latter to open position. 24. A razor blade sharpener having a casing, a plurality of cooperating covers on said casing, cooperating operatively connected rolls mounted in said casing and on said covers and having connections for operation from the exterior of said casing, manually controllable means for retaining said covers in closed position disposed in the path of portions of said covers when moving out of said position, and means for moving said covers upon release of said retaining means toward the latter to open position, said retaining and opening means including resilient connections normally disposing the same in retaining and open position respectively. 25. A razor blade sharpener having a casing, cooperating cover flaps overlying the same and pivoted thereto adjacent their outer ends, cooperating operatively connected rolls mounted in said casing and on said flaps and having connections for operation from the exterior of said casing, means normally throwing said flaps into elevated open position, and manually releasable mechanism acting on the outer ends of said flaps for holding said flaps in closed position. 26. A razor blade sharpener having a casing, cooperating cover flaps overlying the same and pivoted thereto adjacent their outer ends, cooperating operatively connected rolls mounted in said casing and on said flaps and having connections for operation from the exterior of said casing, means normally throwing said flaps into elevated open position, and manually releasable mechanism acting on the outer ends of said flaps for holding said flaps in closed position.

- open position, and manually releasable push button operated mechanism acting on the outer ends of said flaps for holding said flaps in closed position and disposed in said casing and having push buttons extending through the latter. 5
27. A razor blade sharpener having a casing, cooperating cover flaps overlying the same and pivoted thereto adjacent their outer ends, cooperating operatively connected rolls mounted in said casing and on said flaps and having connections for operation from the exterior of said casing, means normally throwing said flaps into elevated open position, flap engaging means inside said casing disposable in the path of movement of portions on the outer ends of said flaps toward opening position and having operating means therefor operable from outside said casing, and resilient means normally disposing said flap engaging means in engaging position and said operating means in operating position. 10
28. A razor blade sharpener having a casing, cooperating cover flaps overlying the same and pivoted thereto adjacent their outer ends, cooperating operatively connected rolls mounted in said casing and on said flaps and having connections for operation from the exterior of said casing, means normally throwing said flaps into elevated open position, flap engaging means inside said casing disposable in the path of movement of portions on the outer ends of said flaps toward opening position and having operating means therefor operable from outside said casing, resilient means normally disposing said flap engaging means in engaging position and said operating means in operating position, and means for eliminating conflict between said flaps and flap operating means upon release of said flaps by said engaging means. 15
29. A razor blade sharpener having a casing with U-shaped side walls, cover flaps with their side walls pivoted to the side walls of said casing, a pair of rolls mounted in the casing, a pair of rolls carried by said flaps, gearing connecting the rolls, means for rotating the gearing, spring means normally tending to throw the flaps open, and yielding means having portions extending through the ends of the casing and having portions normally engaging the edges of said flaps for retaining the flaps in closed position. 20
30. A razor blade sharpener having a casing, cover flaps pivoted to the casing, a pair of rolls mounted in the casing, a pair of rolls carried by said flaps, gearing connecting the rolls, means for rotating the rolls, springs arranged to open the flaps, push buttons mounted in the casing, and springs normally pressing the push buttons outward, the heads of said push buttons, when the buttons are pushed outward, engaging the edges of the inner ends of said flaps and obstructing the opening movements of the flaps. 25
31. A razor blade sharpener having a casing, cover flaps pivoted to said casing and having resilient means normally holding the same in open position and depending portions on said flaps movable inside the ends of the casing and having slots in said portions, rolls carried by said casing and said flaps, means for rotating the rolls, resiliently mounted abutments engageable with said depending portions in the closed positions of said flaps and holding the same closed, and push buttons connected to said abutments and operable to release the same having portions disposed in said slots in the open positions of said flaps. 30
